UNITED STATES PATENT OFFICE

LETTY M. MONTGOMERY, OF NEW YORK, N. Y., ASSIGNOR TO KARRY KART INCORPORATED, OF NEW YORK, N. Y., A CORPORATION OF NEW YORK

DESIGN FOR A BABY CARRIAGE

Application filed September 26, 1931. Serial No. 41,240. Term of patent 14 years.

To all whom it may concern:

Be it known that I, LETTY M. MONTGOMERY, a citizen of the United States, residing at No. 140 West 92nd Street, in the city, county, and State of New York, have invented a new, original, and ornamental Design for Baby Carriage, of which the following is a specification, reference being had to the accompanying drawings, forming part thereof.

I claim:

The ornamental design for a baby carriage, as shown.

LETTY M. MONTGOMERY.
